UNITED STATES PATENT OFFICE.

CARL A. FAIRBANKS, OF WICHITA, KANSAS.

CONTROLLING DEVICE FOR ELECTRIC SIGNS.

Application filed March 27, 1922. Serial No. 547,315.

To all whom it may concern:

Be it known that I, CARL A. FAIRBANKS, a citizen of the United States, residing at Wichita, in the county of Sedgwick and 5 State of Kansas, have invented new and useful Improvements in Controlling Devices for Electric Signs, of which the following is a specification.

This invention relates to a controlling device for an electric sign of the type illustrated and described in the United States Patent Number 1,343,141, granted June 8, 1920. The sign therein disclosed includes the representation of a portion of the human 15 body and especially of the spinal column and some of the nerves directly associated therewith, and the mechanical structure includes means for imparting movement at intervals to certain of the vertebrae, for the purpose 20 therein disclosed.

The present invention deals chiefly with improved means for imparting movement to these vertebrae, it being understood, however, that the operating means may be applied to any group, to individual elements or to all of the vertebrae, with illuminating means similar in principle to those disclosed in the aforesaid patent,—although the illuminating means do not constitute essential 30 features.

A further object is to provide, in connection with a motor driven shaft, and a plurality of cams rigid therewith,—a rocking arm for operation by each cam, and means actuated by said arm for actuating an element indicating displacement of a particular vertebra of the spinal column.

In the drawings, Figure 1 is a face view of the device, showing particularly the chart 40 referred to below; Figure 2 is a view, in elevation, of a portion of the operating mechanism; Figure 3 is an elevation of the remainder of the operating mechanism, including the motor, cam shaft and rock shaft; Figure 4 is an elevation of the make and break mechanism, mounted on the cam shaft; Figure 5 is a vertical transverse section through the gear casing, at the right of the fan of Figure 3; Figure 6 shows the 45 mounting of the movable vertebra 34; Figure 7 is a detail view of one of the cams and rocking arms, for actuating a connecting rod by means of which shaft 32 is rocked, for moving the vertebra.

50 Proceeding to the description of the mechanism for actuating a cam shaft and suitable

make and break devices,—the reference number 10 indicates a motor which includes an armature shaft 11 carrying a fan 12, and projecting into the gear casing 13 mounted 60 on the base 14. The shaft is provided with a worm 15 meshing with a worm wheel 16 on the shaft 17, and the shaft last named carries a worm 18 meshing with worm wheel 19 on the cam shaft 20.

65 In the present instance four cams are shown, these elements being designated 21, 22, 23 and 24. Pivotaly mounted on shaft 25 are rocking arms 26, 27, 28 and 29, these arms being illustrated as of channel shape, 70 the cam devices operating within the channels.

Connected with each rocking arm is a wire or connecting rod such as 30, this element being pivoted, or loosely connected 75 with arm 31 of rock shaft 32 mounted in bearings 33. On the opposite ends of each rock shaft is an element 34 representing a vertebra.

Openings 35 are provided in the chart 36 80 and the particular vertebra 34 to be moved, for indicating abnormal conditions, are visible through the openings, the remaining vertebrae being illustrated on the chart.

In connection with the foregoing arrangement and construction, electric lamps are positioned in such manner as to best attract attention to the condition which the device is intended to emphasize. As a certain lighting arrangement has been fully described in connection with the patent before mentioned, the circuits to be employed in connection with the present sign need not be described in detail, but as the make and break mechanism is operated directly from the cam shaft, it is proper to state that the contact disks 41 and 42 carried by and driven by cam shaft 20, carry metallic segments, through which the circuits are completed, several pairs of brushes 44 being 90 mounted as shown on the insulating plates 47 and 48. Associated with each brush is a wire terminal 50, and a common lead or return is designated 51.

Having thus described my invention, I 105 claim:

1. In a device of the class described, a cam shaft, a cam rigid thereon, an element representing a portion of the human anatomy subject to displacement, a chart with 110 which said element is associated, means for mounting said element to permit of move-

- ment for attracting attention, the chart having a cut away portion through which the element specified is visible, and means for actuating said element from the cam.
5. 2. In a device of the class described, a cam shaft, a cam rigid thereon, a second shaft, a rocking arm pivoted thereon and actuated by the cam, an element representing a portion of the human anatomy and mounted for movement to indicate an abnormal condition, a rock shaft for mounting said element, and means for actuating the rock shaft from the rocking arm.
10. 3. In a device of the class described, a cam shaft, a cam rigid thereon, a second shaft, a rocking arm pivoted thereon and actuated by the cam, an element representing a portion of the human anatomy and mounted for movement to indicate displacement, a rock shaft for mounting said element, and means for actuating the rock shaft from the rocking arm, said means last named including an arm on the rock shaft, and a connecting rod.
15. 4. In a device of the class described, a cam shaft, a cam rigid thereon, a second shaft, a channeled rocking arm pivoted thereon, the cam operating in the channeled portion for moving the arm about its pivotal mounting, a display element to be given a vibratory movement, a rock shaft for mounting said element, and means for rocking the shaft last named upon the operation of the rocking arm.
20. 5. In a device of the class described, an electric motor including a shaft, a worm carried by the shaft, a worm wheel meshing with the worm, a cam shaft, worm gearing driven by the aforesaid worm and worm gear wheel, a cam rigid on the cam shaft, an additional shaft, a rocking arm pivoted thereon and positioned to be moved by the cam, intermittently, a display element to be given a vibratory movement, and means for imparting such movement upon the rocking arm.

In testimony whereof I affix my signature.
CARL A. FAIRBANKS.
